UNITED STATES PATENT OFFICE.

CHARLES F. MEGOW, OF DETROIT, MICHIGAN.

TRACTOR.

1,272,491.

Specification of Letters Patent. Patented July 16, 1918.

Application filed March 16, 1917. Serial No. 155,165.

To all whom it may concern:

Be it known that I, CHARLES F. MEGOW, a citizen of the United States of America, residing at Detroit, in the county of Wayne 5 and State of Michigan, have invented certain new and useful Improvements in Tractors, of which the following is a specification, reference being had therein to the accompanying drawings.

- 10 This invention relates to tractors, and the primary object of my invention is to provide a tractor having gearing mechanisms embodied in the wheels thereof and associated with these mechanisms is a novel 15 steering or controlling mechanism that permits of the speed of one wheel being increased and the speed of another wheel retarded and in this manner the tractor is steered or guided in a desired direction.
- 20 A further object of my invention is to provide a tractor construction wherein the rear axle, rear wheels and power transmitting mechanism have all parts compactly assembled and constructed with a view of reducing the cost of manufacture.

25 My invention will be hereinafter described and then claimed, and reference will now be had to the drawings, wherein—

- Figure 1 is a plan of the tractor;
30 Fig. 2 is a side elevation of the same;
Fig. 3 is an enlarged plan of the tractor, partly broken away and partly in section, and

Fig. 4 is a side elevation of a tractor 35 wheel, partly in section.

In describing my invention by aid of the views above referred to, I desire to point out that the same are intended as merely illustrative of an example by which my invention may be put into practice, and I do not care to confine myself to the precise construction and arrangement of parts shown. The following description is therefore to be broadly construed as including 40 such substitute constructions and arrangement of parts which are the obvious equivalent of those to be hereinafter referred to.

In the drawings, 1 denotes a frame provided with a power plant 2, a drive shaft 3, and the end of the frame 1 is supported by one or more pony wheels 4.

5 denotes a cylindrical or hollow housing or rear axle at the opposite end of the frame 1, and journaled in the housing is a semi-

floating driven shaft 6 having a beveled gear wheel 7 meshing with a beveled gear wheel 8 on the drive shaft 3.

9 denotes a cap on each end of the housing or rear axle 5 and each cap has a peripheral flange 10 and an inner hub member 11 besides an opening 12 that permits of the end of the driven shaft 6 extending therethrough.

13 denotes anti-frictional bearings, in the inner hub member 11 supporting the end of the driven shaft 6, and these bearings are retained in place by a plate 14 suitably connected to the end of the inner hub member 11.

15 denotes a large gear wheel rotatable on the flange 10, said gear wheel having a sleeve 16 free to revolve on the inner hub member 11. The outer end of the sleeve 16 has a gear wheel 17.

18 denotes an outer hub member free to revolve on the sleeve 16 of the large gear wheel 15, and this outer hub member is part of one of two wheel members 19 and 20 spaced apart and disposed in parallelism. The wheel members 19 and 20 have peripheral flanges 21 riveted or otherwise connected to tread pieces 22 and said wheel members are furthermore connected by tie rods 23 adjacent a drum or casing 24 between said wheel members, said drum or casing being fitted on circumferentially disposed flanges 25 on the confronting faces of the wheel members.

26 denotes a plurality of shafts mounted in the wheel members 19 and 20 and on these shafts are double gear wheels, each having a small gear wheel 27 meshing with the gear wheel 17, and a large gear wheel 28. The large gear wheels 28 mesh with a gear wheel 29 fixed on the outer end of the driven shaft 6, and easy access is had to the outer end of the driven shaft by removing a cap 30 connected to the outer wheel member 20.

31 denotes bearings forming part of the caps 9 and 32 denotes bearings carried by the housing or rear axle 5. Journaled in the bearings 31 and 32 are longitudinally alining shafts 33 having the outer ends thereof provided with small gear wheels 34 meshing with the large gear wheel 15. The confronting ends of the shafts 33 have beveled gear wheels 35 and meshing with these beveled gear wheels is a horizontally dis-

posed gear wheel 36 on the lower end of a vertically disposed shaft or steering column 37 that is journaled in a bearing 38, carried by the frame 1. The upper end of the shaft 6 or column 37 has a suitable hand wheel 39.

In operation, the large gear wheels 15, small gear wheels 34, shafts 33, beveled gear wheels 35 and 36, and the shaft or steering column 37 remain stationary and power is transmitted to the traction wheels from the driven shaft 6 through the central gear wheel 29, double gear wheels 28 and 27 and the normally stationary gear wheels 17.

By rotating the shaft or steering column 37, the large gear wheels 15 will be revolved in different directions, consequently the gear wheels 17 will be rotated in opposite directions and one gear wheel will tend to reduce the speed of one of the traction wheels, while the other gear wheel will increase the speed of its traction wheel. In this manner the tractor may be steered and guided through the gearing mechanism located within the traction wheel. To reduce the weight of these wheels the wheel members 19 and 20 are cut away to provide a spoke formation, and any suitable tread members may be mounted upon the peripheries of the wheel members.

From the foregoing it will be observed that the tractor or vehicle has a semifloating driven shaft and that since the load is carried by the inner wheel members it is possible to remove a differential or reduction gear mechanism and still sustain the load. In other words, the gearing mechanism is not subjected to any stresses or strains due to the load on the vehicle frame. It will also be noted that the power plant may be located at any place about the housing or rear axle part.

What I claim is:—

1. In a tractor, traction wheels, gearing mechanism in each wheel, means for operating said gearing mechanism, and manually actuated means common to said gearing mechanisms adapted for regulating the speed of said wheels.

2. In a tractor, a frame, a housing supporting said frame, traction wheels at the ends of said housing, a semifloating driven shaft extending through said housing into said traction wheels, gearing mechanisms at the ends of said shaft and operated thereby for imparting movement to said traction wheels, and means operable relative to each gearing mechanism adapted for simultaneously controlling the speed of each wheel.

3. In a tractor, a housing, traction wheels at the ends thereof, a semifloating driven shaft extending through said housing into said wheels, a gearing mechanism in each wheel operated by said shaft adapted for imparting movement to said traction wheels, each gearing mechanism including a manually adjusted gear wheel adapted for regulating the speed of the gearing mechanism.

4. In a tractor, a frame, a housing supporting said frame, a semifloating driven shaft extending through said housing, traction wheels supporting the ends of said housing, a variable speed mechanism in each wheel operated by said semifloating driven shaft, and means carried by said frame common to said wheels for controlling the variable speed mechanism in each traction wheel.

In testimony whereof I affix my signature in the presence of two witnesses.

CHARLES F. MEGOW.
